HUGH G. GREENFIELD, OF TACOMA, WASHINGTON, ASSIGNOR OF ONE-HALF TO VARIETY MACHINERY COMPANY, OF TACOMA, WASHINGTON, A CORPORATION OF WASHINGTON.

VENEER-TAPING MACHINE.

Application filed October 11, 1926. Serial No. 140,774.

This invention relates to machines for applying a strip of paper tape to the edges of veneer sheets and has for its objects, first, to provide means whereby the length of time 5 elapsed between the wetting of the gummed surface of the paper tape and its application to the sheet of veneer is substantially constant independent of the speed of feed of the veneer through the machine; second, to provide means whereby the said elapsed time 10 may be adjusted to suit varying conditions of atmospheric humidity and temperature, or for varying conditions of, or kinds or brands of tape; third, to provide means whereby the 15 speed of the veneer fed through the machine may be easily and quickly changed, thereby enabling the operator to run all lengths and grades of veneer through the machine without having to stop the machine to shift 20 his belt from one pulley to another and without having to manually change the path of the tape from the water bath to the veneer in order to alter the length of exposed wet 25 tape; and fourth, to provide means whereby the wet tape may be guided to one side of the center of the feed mechanism thereby adapting it for taping the edges of sheets of veneer.

I attain these and other objects by the devices, mechanisms, and arrangements illustrated in the accompanying drawings, in which—

Fig. 1 is a side elevation of my improved machine; Fig. 2 is a plan view of the tape 35 guiding means for taping the ends of sheets of veneer; Fig. 3 is a horizontal section on the line 3—3 in Fig. 4; Fig. 4 is a front elevation of a portion of the taping machine; and Fig. 5 is a section of the variable 40 speed drive of the taping machine, showing the belt shifting means mounted thereon.

Similar numerals of reference refer to similar parts throughout the several views.

It is well known practice, in working with 45 very thin sheets of veneer, to apply a strip of paper tape to the edges of the sheet, or to apply a similar strip of tape to both adjacent edges of two sheets of veneer. This machine is adapted to apply the tape in 50 either way by applying or removing a part thereof to cause the tape to be run either to one side of the center or on the center, as the case may be. The speed at which the sheets of veneer may be fed through the

machine depends partly on their size, their 55 dryness and their distortion. It has been customary to change the speed of the feed by stopping the machine and shifting the belt to different size pulleys thereby either stepping it up or down. To overcome this 60 waste of time and labor I have provided a means of shifting the speed by gradual change from one speed to another by simply turning a crank handle.

When the gummed surface of the paper 65 tape has been moistened, a certain definite time should elapse before it is applied to the wood veneer, in order to give the moisture, which has been spread on its outer surface, time to penetrate into the gum material and suitably soften it. Since the rate 70 of feed of the tape is necessarily exactly equal to that of the veneer it is evident that, unless special provision is made, the tape will occupy less time in passing from the water bath to the veneer if the veneer feed is fast 75 than it will if the feed is slow, and that therefore the moisture will have less time to penetrate and soften the gum. Also, it is a fact that the tape must not be allowed 80 to stay moist any longer than is absolutely necessary to soften the gum, and therefore it is not a sufficient solution of the problem 85 to cause the tape to pass through a permanently long course because, though such a course might be sufficient when the speed is fast, it will probably be much too long when the speed is slow. I have therefore provided a means, tied up to the feed control, whereby the length of the course of 90 the tape from the water bath to the veneer is substantially proportionate to the speed 95 of feed of the veneer and therefore the elapsed time of exposure of the moist tape is substantially constant.

However, it is also a well known fact that the atmospheric condition of the room has a strong effect on the moist tape in that, if the air be dry or warm, the moist tape should not be exposed for as long a time 100 as when it is cool or moist. Also the kind of gum, the age of the tape, the kind of tape, and many other variable conditions make it desirable to provide a different length of exposed moist tape for the same 105 rates of feed. Since these conditions only vary slightly and require adjustment at comparatively long intervals I have provided a

means whereby the course traveled by the tape may be manually adjusted to suit the particular conditions as above outlined.

Referring now to the drawings, it will be seen that my machine comprises a frame 1, having a horizontal table 2, adapted to support the veneer to be taped, and an arm 3, extending over the center of the table 2 and carrying the taping apparatus on a head 4. 10 A feed roller 5 is mounted below, and extends up through the table 2, and is adapted to engage the lower side of the veneer sheet and to cause it to travel on the table and under the taping apparatus. A pressure roller 15 6 is mounted in the head 4 and engages the upper side of the veneer sheet and applies the moist tape thereto. The feed roller 5 is driven by a shaft 7, and the pressure roller 6 is driven by the shaft 8. Both these 20 shafts 7 and 8 are driven, through suitable intermediate gears, or otherwise, from a variable-speed drive mechanism one form of which is illustrated herein and comprises the cone pulley 9, driven by the belt 10 from a 25 complementary driving cone pulley 11, which rotates at a constant speed. The belt 10 is adapted to be placed in any position on the pulleys 9 and 11 and therefore the peripheral speed of the feed roller 5 and the 30 pressure roller 6 may be changed by shifting the belt from one position to another. The above method of obtaining a variable speed from a constant drive is one form of many such known drives, any one of which may be 35 used in this machine if they are adapted thereto.

In the form of speed control, illustrated herein, I mount a horizontal shaft 12 on the upper frame arm 3 and rotate it by means of 40 a pair of miter gears 13 and by the hand wheel 14 and the crank handle 15. A vertical shaft 16 is mounted at the rear of the machine and is driven by the shaft 12 by means of the pair of bevel gears 17. A horizontal screw-threaded shaft 18 is mounted equidistant from and parallel with the axes 45 of the two cone pulleys 9 and 11 and is driven from the vertical shaft 16 by a pair of bevel gears 19. A guide rod 20 is mounted 50 parallel with the shaft 18 (Fig. 5). A belt shifting carriage 21 is mounted on the rod 20 and on the shaft 18 and has a nut 22 engaging the threads of the said shaft 18. The belt 10 passes through two holes 23 in 55 the said carriage 21. Thus, by rotating the hand wheel 14, the shafts 12, 16 and 18 are rotated and the carriage 21 is shifted along the shaft 18 and the rod 20 and shifts the belt 10 on the complementary cone pulleys 60 9 and 11.

Referring particularly to Fig. 4, it will be seen that the roll of tape 24 is mounted on an arm 25 extending horizontally from a vertical frame 26 attached to the head 4 on the 65 end of the upper arm 3 of the frame. The

usual water bath 27 is mounted below the said arm 25 and is provided with a series of suitable guide rollers 28 and wetting rollers 29 mounted therein and adapted to support and guide the paper tape therethrough. 70

A variable-course tape-guiding mechanism is provided and comprises a vertical screw-threaded shaft 30, mounted in the said vertical frame 26, and is driven by the above-described horizontal control shaft 12 through 75 the bevel gears 31. A nut 32 engages the screw shaft 30 (Fig. 3) and is kept from turning therewith but is free to travel vertically thereon in the said frame 26. A pin 33 passes out from the nut 32 and is provided with screw-threads and with a wing nut 34. A vertical plate 35 is provided with a longitudinal slot 36 and the wing nut 34 80 clamps the plate 35, in any adjusted position, to the nut 32. A guide roller 37 is mounted 85 on one end of the plate 35 and is in line with the guide rollers 28 on the water bath, and is in the central axis of the veneer feed. It is evident, then, that when the shaft 12 is rotated to change the speed of feed of the 90 veneer, as above described, it also turns the shaft 30 and raises or lowers the nut 32, the plate 35 and the roller 37. The tape 24 passes from the guide roller 28 to, and over, the said adjustable roller 37, and then down 95 to be applied to the veneer; therefore, as the roller 37 is raised or lowered, the length of tape between the water bath and the veneer is lengthened or shortened by substantially double the amount of movement of the nut 100 32 in the frame 26. The apparatus is arranged so that as the speed of the veneer feed is increased the length of exposed tape between the water bath and the veneer is substantially proportionately increased. 105

Also, it will be seen, that the actual length of exposed moist tape between the water bath 27 and the veneer may be periodically adjusted by loosening the wing nut 34 on the pin 33 and sliding the plate 35 up or down over the said pin, and then clamping it thereto by tightening the said wing nut 34 again. Also, in extreme cases, it will be seen that the entire plate 35 may be reversed from the position shown in the drawings, bringing the roller 37 to its upper end, instead of its lower end as shown, and thereby permitting a much longer time to elapse between the moistening and applying of the tape than would be possible when placed as shown, such position being used when the veneer is being fed through at a high rate but the gummed tape requires an extra long time to become suitably softened. 115 120 125

When it is desired to apply the tape to the edge of a sheet of veneer the tape 24 is led over a series of inclined adjustable rollers which divert it from the central line of the veneer feed (Figs. 1, 2 and 4). A bar 38 is 130 removably and adjustably secured to the up-

per side of the table 2 by thumb-screws 39 which pass through transverse slots in the said bar 38 and screw into the said table 2, thus permitting a limited transverse adjustment of the bar 38 on the table. An arm 40 extends from the bar 38 and carries a vertical pin 41, which is bent at right-angles at its end, and carries a horizontal guide roller 42 thereon. The pin 41 is clamped to the arm 40 by means of a thumb-screw 43 and therefore it may be adjusted in height above the table 2 (Fig. 4) and in horizontal angle (Fig. 2). Another arm 44 extends up from the bar 38 and carries the horizontal pin 45, whose axis lies parallel with the bar 38, and with the direction of feed of the veneer, and which is also bent at right-angles at its end and carries a guide roller 46 thereon. The pin 45 is clamped to the arm 44 by means of a thumb-screw 47 and therefore the roller 46 may be adjusted in distance from the other pin 41 and in vertical angle (Fig. 4). The tape 24 is therefore led from the water bath 27 over the length adjusting roller 37, then it is led in an inclined downward and rearward direction and is slightly twisted (Fig. 4) and passes over the guide roller 42, which is set at an angle to the direction of travel of the veneer, thence it is led forward and inclined laterally (Fig. 2) and slightly twisted (Fig. 4) and passes under the vertically inclined roller 46 and is thus displaced laterally from the central line of the feed but is parallel thereto, and passes thence under the pressure roller 6, which applies it to the veneer.

Thus it will be seen that the manually-operated control mechanism connects the variable-speed drive mechanism to the variable-course tape-guiding mechanism in such a manner that when the operator of my machine changes the speed of the veneer feed he also changes the length of the exposed moist tape in accordance with the changes in the speed of the veneer feed. The machine also guides the tape to one side of the central line of the feed and is therefore adapted to apply the tape to the edge of single sheets of veneer. In case it is desired to tape the edges of two sheets together, then the bar 38 is removed, by unscrewing the thumb screws 39, and the tape is led directly from the adjusting roller 37 to the pressure roller 6, along the center line of the feed of the machine.

It is evident that many variations may be made in the several parts of this machine without departing from the principles involved therein, for instance, practically any of the various well known variable-speed mechanisms may be substituted for the corresponding mechanism illustrated and described herein.

Having therefore described my invention, what I claim is:—

1. In a veneer taping machine, the combination with a veneer feed mechanism; a variable-speed drive mechanism; a variable-course tape-guiding mechanism; and manually-operated means connecting said variable-speed drive mechanism to said variable-course tape-guiding mechanism, whereby the length of exposed moist tape is increased as the speed is increased to render the time of exposure of the moist tape substantially uniform. 65

2. In a veneer taping machine, the combination with a veneer feed mechanism; a variable-speed drive mechanism; a variable-course tape-guiding mechanism; adjustable means in said variable-course tape-guiding mechanism, whereby the length of the course may be adjusted independent of said variable-course tape-guiding mechanism; and manually-operated means connecting said variable-speed drive mechanism to said variable-course tape-guiding mechanism whereby the said adjusted length of exposed moist tape is increased as the speed is increased 80 to render the time of exposure of the moist tape substantially uniform. 85

3. In a veneer taping machine, the combination with a veneer feed mechanism; a tape-guiding and moistening means adapted to feed the tape in the central axis of the veneer feed; a guide roller mounted in the central axis of the veneer feed and having its axis lying in a horizontal plane but at less than right-angles to the direction of the veneer feed and adapted to receive the 100 tape from the tape guiding means and to divert it from the central axis to an angular course; and a second guide roller mounted to one side of said central axis of the veneer feed and adapted to receive the tape in its 105 angular course and to divert it into a laterally displaced but parallel course to said central axis of veneer feed. •

4. In a veneer taping machine, the combination with a veneer feed mechanism; a tape guiding and moistening means adapted to feed the tape in the central axis of the veneer feed; a horizontally-rotatably-adjustable guide roller mounted in said central axis of veneer feed and adapted to receive 110 the tape from the tape guiding means and to divert it from the central axis to an angular course; and a vertically-rotatably-adjustable guide roller mounted to one side of the said central axis of the veneer feed and adapted to receive the tape in its angular course and to divert it into a laterally displaced but parallel course to said central axis of veneer feed. 115 120
